United States Patent

Des. 238,918
Patented Feb. 24, 1976

238,918

SOAP DISPENSER AND MOUNTING BRACKET THEREFOR

William R. Breen, Toronto, Ontario, Canada, assignor to
W. R. Breen Limited, Rexdale, Ontario, Canada

Filed Jan. 7, 1975, Ser. No. 539,207

Term of patent 14 years

Int. Cl. D6—06

U.S. Cl. D6—95

FIG. 1

FIG. 2

FIG. 3

FIG. 4

FIG. 5

FIG. 1 is a front perspective view of a soap dispenser and mounting bracket therefor in accordance with my design;

FIG. 2 is a rear perspective view thereof;

FIG. 3 is a top plan view thereof;

FIG. 4 is a side elevational view thereof; and

FIG. 5 is a bottom plan view thereof.

I claim:

The ornamental design for a soap dispenser and mounting bracket therefor, as shown.
